UNITED STATES PATENT OFFICE.

WILLIAM J. A. DICKENSON, OF SIOUX FALLS, SOUTH DAKOTA, ASSIGNOR TO MODOC DEVELOPMENT COMPANY, OF SIOUX FALLS, SOUTH DAKOTA, A CORPORATION.

SAFETY-RAZOR.

1,035,548.

Specification of Letters Patent. Patented Aug. 13, 1912.

Application filed December 26, 1911. Serial No. 667,735.

To all whom it may concern:

Be it known that I, WILLIAM J. A. DICKENSON, a citizen of the United States, residing at Sioux Falls, in the county of Minnehaha and State of South Dakota, have invented certain new and useful Improvements in Safety-Razors, of which the following is a specification, reference being had to the accompanying drawings.

10 My invention relates to new and useful improvements in safety razors and more particularly to a blade therefor, and my object is to provide a blade and a guard therefor which shall have close contact with the 15 cutting edge of said blade.

A further object of the invention resides in providing a guard or protection for any and all kinds of razor blades, including such blades as are commonly used in safety 20 razors in general use, said guard being formed of tough, flexible material, such as wire, filament, thread or fiber.

A further object resides in providing a guard for the blade composed of segments 25 of flexible material disposed equidistant from one another throughout the length of the blade and in close contact with the edge thereof, and a still further object resides in providing means for permanently and 30 movably mounting the guard with respect to the blade.

Still another object of the invention resides in providing a device which is extremely simple and durable in construction, 35 inexpensive to manufacture, and one which will be very efficient and useful in operation.

With these and other objects in view, my invention consists in the novel features of construction, combination and arrangement 40 of parts as will be hereinafter referred to and more particularly pointed out in the specification and claims.

In the accompanying drawings forming a part of this application, Figure 1 is a plan view of a razor showing my improved blade 45 applied to use thereon. Fig. 2 is a section therethrough as seen on line 2-2, Fig. 1.

Fig. 3 is an enlarged vertical transverse section through the blade and holder therefor. 50 Fig. 4 is a plan view of a modified form of my invention showing the manner in which the guard is removably mounted in connection with the blade. Fig. 5 is an enlarged transverse section therethrough as seen on

line 5-5 Fig. 4. Fig. 6 is a fragmentary 55 perspective view of a further modified form of holder for the blade also showing means for removably securing the guard with respect to the holder, and, Fig. 7 is an enlarged vertical section through this latter 60 form in its effective position with the blade mounted therein.

In carrying out my invention, I shall refer to the drawings in which similar reference characters designate corresponding 65 parts throughout the several views and in which 1 indicates a handle member such as is used in the usual form of razor, to the one end of which is pivotally engaged an arm or the like 2, said arm being pivoted adjacent one end thereof to permit both ends to project beyond the pivot point as is true in the pivoting of the blade in the usual form of razor, and the portion of the arm 2 which extends a greater degree beyond the 70 pivot point, has a portion thereof increased in width, as shown at 3, to form a seat or resting plate. Also pivoted to the handle 1 on the same pivot point upon which the arm 2 is secured, is an additional arm 4 which is spaced a slight distance from the arm 2 so that a blade may readily fit between the 75 two arms, and the outer portion of said arm 4 is increased in width, as shown at 5, to correspond with the portion 3 of the other 80 arm, while said portion 5 is also provided with a tongue or lip 6' which depends therefrom and is adapted to engage the one edge of the portion 3 of the opposing arm to limit the movement of the arm 4 in the one 85 direction.

As stated, the two arms 2 and 4 are spaced a slight distance from one another to permit of a blade being disposed between the same, and to provide for such a blade, the 90 inner face of the portion 3 of the arm 2 is provided at its ends with a pair of posts or studs 6 and 7 which are adapted to enter the notches 8 formed in the ends of a blade 9. This blade is of such length 100 as to fit snugly between the two studs 6 and 7 when the latter are properly positioned in the notches 8, and said blade is of a greater width than the width of the portion 3 of the arm 2, but in order to dispose one of 105 the cutting edges of said blade some distance beyond the one edge of the portion 3, said pins or studs 6 and 7 are disposed

nearer the one side edge than the other on the portion 3. This blade may be of any preferred type used in safety razors, but is preferably of the double-cutting edge type, having the ends thereof provided with the notches which are disposed in the plane of the longitudinal center of the blade, so that when desired, the cutting edges may be reversed.

10 From the construction shown, it will be appreciated that after the blade is properly positioned on the portion 3 of the arm 2, the arm 4 may be brought into position in alignment with said arm 2 so that the widened portion 5 thereof will cover a greater portion 15 of the blade and retain said blade in position by frictionally engaging the same, and I have provided a guard for the cutting edge of the blade which projects beyond 20 these widened portions of the arms, which guard forms the most essential part of my invention, as will be hereinafter described. To this end, I desire to provide a very fine but tough flexible material 10, 25 such as wire, filament, thread or fiber, the one end of which is secured to one face of the blade by soldering, electric welding or riveting, as shown at 10', and wrapping said flexible connection the full length of the 30 blade so that the segments of wire, thread or the like, will be disposed equidistant from one another and in close contact with the cutting edges, if there be a double edge, of said blade. As stated, this flexible connection 35 extends the full length of the blade, and the opposite end thereof is secured to one face of the blade, as shown at 11', in a similar manner to that referred to at 10', and as this flexible connection, no matter 40 what may be its character, is of a very minute diameter and is wrapped or wound quite tightly about the blade, it will be appreciated that the same will form but very slight projections on the cutting edges of 45 said blade.

As stated above, the pins or studs 6 and 7 are so positioned on the portion 3 of the arm 2 as to dispose a cutting edge of the blade some distance below one side edge of 50 said portion 3, and as the arm 4 is brought to align with the arm 2 having the blade thereon, the inner face of the portion 5 thereof is adapted to frictionally bind against the one face of the blade having the 55 fine flexible guard wrapped thereon to securely retain said blade in position. The downward movement of the arm 4 will be limited with respect to the arm 2 by the lip or tongue 6', but in order to retain said arms 60 4 and 2 in perfect alignment throughout the operation of the device, a flange or lug 11 is provided on the end of the portion 5 which is adapted to be received in a groove, notch or the like 12 formed on the free end of the 65 arm 2.

While I have particularly described a holder for my improved blade, it will be understood that I do not wish to limit myself to this construction described, and may use any form of holder desired which will retain the blade in position to be used upon the blades, as the essential feature of this invention is the blade with the guard therefor.

It will be noted that in the foregoing description, I have described a blade with a flexible guard therefor which is permanently carried thereon, but in this connection, it must be stated that I also do not wish to be limited to a guard which is permanently carried on the blade and may provide a guard formed of similar material to that described above which is brought in close contact with the edge of the blade and removably mounted with respect thereto. To this extent, I provide the various modifications, as disclosed in Figs. 4 to 7, inclusive, the construction of which will be hereinafter and more particularly described.

In Figs. 4 and 5, covering the first of the modified forms, I provide a handle member 13 of the usual or any preferred type, such as is used in the usual form of razor and as shown in Fig. 1, to which is pivoted adjacent one end thereof, an arm 14, said arm being increased somewhat in thickness toward its free end and provided on the inner face of this thickened portion with an oblong recess 15 to receive therein a blade 16. This blade may be of the usual or any preferred form used in safety razors. The one shown in the drawings having a double edge, and this blade is provided on the ends thereof on the longitudinal center of the same, with notches (not shown), such as are provided in the blade 9 in the other form, which notches are adapted to receive studs or the like (not shown) on the rear wall of the recess 15. The retention of the blade in the recess by this means is identical with that shown in the other form, the one cutting edge of the blade being disposed a short distance below the lower edge of the arm 14, and in order to retain this blade against the arm 14 and in the recess 15, an additional arm 17 is provided and pivoted at its one end to the arm 14. This arm 17 is increased in width for a greater portion of its length coincident to the increasing of the width and thickness of the arm 14, and a tongue or lip 18 formed on the upper edge of said arm 17, is adapted to engage the arm 14 to limit the movement of the former with respect to the latter. When this tongue or lip 18 is in engagement with the arm 14, the arm 17 will be in perfect alignment with said arm 14, and the inner face of said arm 14 will bind tightly against the one face of the blade 16 to retain the latter in position, while one edge of said blade projects beyond 125

the lower edges of the arms 14 and 17 to permit the same being used for shaving in the usual manner. As stated, this form contemplates the use of a guard to be removably mounted on the device with respect to the 5 blade, and to this extent, the upper or rear edges of the arms 14 and 17 are provided with a plurality of alining notches 19 which are arranged equidistant from one another, 10 while the outer faces of each of the arms 17 and 14 are provided with a plurality of guide channels or grooves 20 which terminate at one of their ends in the notches 19 and are slightly inclined on the faces of said 15 arms 14 and 17, respectively. The upper or rear edge of the arm 17 is provided adjacent its ends with a pair of binding posts 21 and 22, to one of which is engaged the one end of my improved flexible guard 23 which comprises a wire, filament, thread or fiber wrapped or wound about the arms 14 and 17 in close contact with the projecting cutting edge of the blade 16, while the other of said binding posts receives the opposite end of said 20 flexible guard, after being wound about the device. The segments of this flexible guard 23 are received in the notches 19 in the rear edges of the arms 14 and 17 and guided on the side faces of said arms by means of the guide 25 channels or grooves 20, so that said segments will be disposed equidistant from one another throughout the length of the blade, and as said segments are drawn tightly in close contact with the cutting edge of the 30 blade, the same will form but slight projections thereon. The ends of the flexible guard 23 are, as stated, engaged, respectively, with the binding posts 21 and 22 in such a manner as to be readily removed when desired, 35 so that the operator may, at will, remove the same and apply a new blade or reverse the cutting edges thereof with little or no trouble.

In Figs. 6 and 7, I have shown a still further modified form of the invention which 40 also contemplates the use of a flexible guard removably carried on the device with respect to the blade thereon, and in this form, I have shown an arm 24 which may, itself, 45 be engaged with a handle (not shown), said arm being increased in width and thickness at its free end and provided with an oblong recess 25 in this thickened portion. This recess 25 forms a seat for a blade 26, said recess being provided adjacent its ends with 50 the studs 27 which are adapted to enter notches (not shown) in the ends of said blade 26, as described in connection with the other forms. When this blade 26 is properly 55 mounted in the seat, the one edge thereof projects below the lower edge of the arm 24, and in order to retain said blade in said seat 25, a plate 28 is provided which is hinged, as 60 shown at 29, to the rear edge of the increased portion of said arm 24. This plate 65

28 is of a size equal to that of the increased portion of the arm 24, and when brought in position against said increased portion, the inner face of said plate 28 will contact with the one face of the blade 26 mounted in said 70 recess.

The rear edges of the widened portion of the arm 24 and the rear edge of the plate 28 are provided with alining transverse notches 30, while the outer side faces of each of said 75 members are provided with the guide channels or grooves 31 which are slightly inclined and terminate at their upper ends in the notches 30. The outer face of the arm 24 is provided adjacent the ends of the thickened portion thereof with a pair of binding posts 32 which receive the ends of a flexible guard 33, said guard being formed of wire, filament, thread or fiber, as in the other form, and wrapped around the plate 80 85 90 95 100 105 110 115 120 125 130

28 and the widened portion of the arm 24. This flexible guard 33, as in the form shown in Figs. 4 and 5, has the segments thereof guided through the notches 30 and the channels or grooves 31 to dispose said segments equidistant from one another throughout the length of the blade, and said guard is drawn in close contact with the cutting edge of the blade to provide very slight projections thereon. Thus, from the form shown in this modification, and also from the form in the other modification, it will be seen that a safety razor set embodying these improvements, will consist merely in a holder, a number of blades and a spool of the flexible material used as a guard, it being understood that when a blade is desired to be changed, the guard may be readily removed by the operator in accomplishing the desired result.

From the foregoing, it will be seen that I have provided an improved safety razor wherein the blade is provided with a guard or projection formed of a very tough flexible material which is brought in close contact with the cutting edge of said blade, and it will further be seen that the guard comprises segments of a flexible material arranged equidistant from one another throughout the length of the blade. Furthermore, it will be seen that I have provided a means for both permanently and removably mounting the guard with respect to the blade, both forms embodying the use of a flexible guard, the segments of which are brought into close contact with the edge of the blade and arranged equidistant from one another throughout the length thereof.

While I have described several forms of holders in connection with the blades to which the guards are applied, I desire to have it understood that any form of holder, whatsoever, may be used, the principal idea of the invention contemplating the use of a flexible guard, the segments of which are

4
brought in close contact with the cutting edge of the blade and arranged equidistant from one another throughout the length thereof. In this connection, it must be stated that various changes in form, proportion and in the minor details of construction may be resorted to without departing from the spirit or sacrificing any of the principles of the invention.

10 It will still further be seen that my device is extremely simple and durable in construction, inexpensive to manufacture, and one which is very efficient and useful in operation.

15 What I claim is:—

1. In a safety razor, a blade and a guard applied thereto comprising a plurality of longitudinally spaced segments held in contact with the cutting edge and extended on

20 opposite faces of said blade.

2. In a safety razor, a blade and a guard therefor consisting of a continuous flexible winding extending around said blade and across the cutting edge thereof, and means to

25 secure the ends of said winding for retaining

the convolutions thereof in contact with the cutting edge of the blade.

3. In a safety razor, a blade and a guard therefor comprising a flexible material wrapped around said blade across the cutting edge thereof, the convolutions of said flexible material being spaced at regular intervals throughout the length of the blade, and means to secure the ends of said flexible material for retaining the convolutions thereof in contact with the cutting edge of the blade.

4. In a safety razor, a blade and a flexible material wrapped therearound in engagement with the cutting edge of the same to form a guard therefor, and means to permanently mount the ends of said flexible material under tension on the face of said blade.

45 In testimony whereof I hereunto affix my signature in the presence of two witnesses.

WILLIAM J. A. DICKENSON.
